UNITED STATES PATENT OFFICE.

GEORGE M. PHELPS, OF BROOKLYN, NEW YORK.

IMPROVEMENT IN PRINTING-TELEGRAPHS.

Specification forming part of Letters Patent No. 91,662, dated June 22, 1869.

To all whom it may concern:

Be it known that I, GEORGE M. PHELPS, of Brooklyn, in the county of Kings and State of New York, have invented and made a new and useful Improvement in Printing-Telegraphs; and I do hereby declare the following to be a full, clear, and exact description of the said invention, reference being had to the annexed drawing, making part of this specification, wherein—

Figure 1 is a general plan of my instruments, showing the electric circuits. Fig. 2 is an elevation of the printing mechanism. Fig. 3 is a section at the line $\alpha\alpha$.

Similar marks of reference denote the same parts.

This invention relates to that class of telegraph instruments that make use of a type-wheel revolved by electricity to print upon a strip of paper.

My invention consists in a pneumatic circuit-changer, applied in such a manner that when the vibrations of the magnet that moves the type-wheel cease, the pneumatic circuit-changer operates to throw the current through a magnet that gives the impression, and as soon as the magnet that moves the type-wheel is again charged, the movement produced operates the pneumatic circuit-changer, and throws the current through a magnet that draws the roller and paper away from the type-wheel. I also make use of a double-acting relay that causes a movement to be given to the type-wheel when the circuit is broken, and another when it is closed, thereby facilitating the operation, and causing the instrument to operate with greater rapidity than heretofore.

In the drawing, a is a dial with signs or letters; b , the index-pointer, revolved on a center stud that is connected with the binding-screw e ; and d is a circuit-breaker, formed with notches corresponding in number to half the number of character-spaces, there are around the dial a , and v is a circuit-closer on b , so that the circuit from e and e' , through the main telegraph-line, is closed when the pointer b is at one letter, and broken at the next. The relay instrument, with its magnet d' , is placed in the main line, and the local battery e connects by the binding-screw e' with both the magnets f and g . The magnet g is in

the circuit to the binding-screw g' , and the magnet f in the circuit to the screw f' . The armature 3 of the magnet d' is connected to the screw 4, and thence to the battery e . Upon the armature is a double-ended circuit-closer, 5, and 6 and 7 are adjustable points on the line of the closer 5, so that when the magnet d' is charged, the circuit is closed through 5 and 6, binding-screws 38, and g' , and the magnet g , and at the same time the circuit through 7, 8, f' , and f is broken. When the circuit through the main line and magnet d' is broken, the spring 9 draws the armature 3 connecting 5 and 7, and throwing the circuit through the magnet f , so that the magnet g is operated every time the index-pointer closes the circuit for one letter, and the magnet f when the circuit is broken in denoting the next letter. The magnets f and g have armatures 10 and 11 attached to a lever, h , that vibrates upon an axis, 12, and gives a motion of one letter or space to the type-wheel each time the lever is moved either one way or the other, so that the revolution of the type-wheel k and index-pointer will be isochronal. The lever h is made with two arms, having V-shaped inclined ends or propelling pallets, as seen by dotted lines in Fig. 1, and upon the arbor k' of the type-wheel k is a wheel, l , with pointed teeth, the teeth being half the number of the letters or spaces on the wheel k , so that the inclined end of one arm, passing in between the pointed teeth, moves the wheel k around one letter, and then the other incline of the other arm moves it around the next letter as the alternate pulsations of electricity pass through first one magnet and then the next. An inking-wheel, m , is kept in contact with the type-wheel by a spring, so as to ink the surfaces of the types. The impression is made by the roller n that is set on an arm, n' , that swings upon the stud 14. o and p are armatures attached to the arm n' , and q and r are magnets to the respective armatures.

When the circuit is closed to q , the roller n will be brought with a blow against the type upon k , that is in position for printing, and when the magnet r is charged the roller n and arm n' will be swung back. I allow a slight movement to the roller n by mounting its stud 15 upon an arm, 16, that swings upon the stud 17 on n' . The spring 18 throws the parts off

the type-wheel instantly that the blow is given of the roller and paper on the type, so that the impression will not be blurred by the movement of the type-wheel. The paper (shown by blue lines in Fig. 1) passes through a guide, *i*, and between the roller *n* and a divided spring, 19, that presses on the top and bottom portions of the strip of paper. The feed-motion of the paper results from the pawl 20 taking ratchet-teeth on the roller *n* as that is brought back by the magnet *r*.

My pneumatic circuit-changer is provided to direct the electrical current from the battery *s* through the magnet *r*, when the type-wheel is being moved, and through the magnet *q* when the same stops and the impression is to be made.

An arm, *t*, is provided extending from the lever *h*, or its axis, and acting upon the inclined end of the circuit-changer *v* lifts that and presses up the piston *u* in the cylinder *w*. The valve 21 allows the free escape of air, and the piston is partially held up by the atmosphere, so that the circuit-closer *v* is relieved of its weight, and the points 22 and 23 are kept together by the spring 24, and the electricity passes through the binding-screw 25, insulated plate *v'*, spring 24, circuit-changer *v*, points 22 23, and wire to the magnet *r*, (to draw back the roller,) and thence to the battery *s*. This continues while the lever *h* and arm *t* are vibrated; but as soon as a sufficient pause occurs, the piston *w* descends gradually, and by its weight moves the changer *v*, separating 22 and 23, and closing the circuit through the insulated screw 26 and connection from the plate 27 to the magnet *q*, thereby breaking the circuit to the magnet *r*, and causing the magnet *q* to give the impression by a blow upon the types, as aforesaid.

The general operation of this apparatus as a whole will be fully understood from the foregoing, and I remark that I do not limit myself to the precise position of the parts shown, as the placing of them may be varied for convenience.

I am aware that a type-wheel has been moved by pawls and a ratchet-wheel; also, that an electrical clock has been moved by pallets. In my improvement the type-wheel is both moved and held by alternately acting wedge-shaped pallets.

What I claim, and desire to secure by Letters Patent, is—

1. The combination of a magnet, double wedge acting pallets, pallet-wheel, type-wheel, and printing mechanism, substantially as and for the purposes described.
2. The combination of two electro-magnets, *f g*, with the armatures 10 11, lever *h*, pallets, wheel *l*, and type-wheel *k*, substantially as set forth.
3. The pneumatic circuit-changer, constructed substantially as specified, and combined with a magnet or magnets for giving or allowing a gradual movement when the vibration of the magnet ceases, substantially as set forth.
4. The combination of the spring 18 with the impression-roller *m*, swinging arm *n'*, and electro-magnet operating the same, in the manner and for the purposes substantially as set forth.

In witness whereof I have hereunto set my signature this 31st day of August, A. D. 1868.

GEO. M. PHELPS.
